J. E. McCAFFERTY.

SCREW DRIVER,

APPLICATION FILED DEC. 30, 1920.

1,423,722.

Patented July 25, 1922.

Inventor

James E. McCafferty
By his Attorney

W. T. Ciswell.

UNITED STATES PATENT OFFICE.

JAMES E. McCAFFERTY, OF NEWARK, NEW JERSEY.

SCREW DRIVER.

1,423,722.

Specification of Letters Patent. Patented July 25, 1922.

Application filed December 30, 1920. Serial No. 434,009.

To all whom it may concern:

Be it known that I, JAMES E. McCAFFERTY, a citizen of the United States, and a resident of Newark, in the county of Essex and State 5 of New Jersey, have invented certain new and useful Improvements in a Screw Driver, of which the following is a full, clear, and exact specification.

This invention relates to a class of working tools.

My invention has for its object primarily to provide a tool or driving device designed to be employed for tightening and loosening screws, bolts and the like in other articles 15 in a manner whereby the necessity for removing the tool from its engagement with the screw to continue its rotation after being partly revolved will be obviated, in order to facilitate the manipulation of the screw, 20 and which also contemplates the provision of lockable parts of the tool so that if desired it may be used in a fashion similar to operating screw drivers of ordinary types. The invention consists essentially of a handle 25 with a socket having in its entrance a fixed protruding annular row of spaced lugs. In the socket interiorly of the lugs is rotatably mounted one end of a bit or blade adapted to removably engage the seat of the head of 30 a screw or bolt for being revolved, and the bit is also yieldingly movable inwardly and outwardly of the socket. Projecting from the bit is a single tooth member or pin designed to be removably inserted in the spaces 35 between the lugs when the bit is forced inwardly of the socket of the handle so that the bit and handle may be simultaneously revolved, in order to avoid separation of the bit from the screw when it is desired to turn 40 the screw a number of rotations.

Another object of the invention is to fix on the bit a cap which also rotatably surrounds the socketed part of the handle; and still another object of the invention is to 45 provide a lock for releasably locking the cap and handle so that the bit will be held against independent rotation of the handle.

A further object of the invention is to provide a screw driver of a simple and 50 efficient construction which may be made in various sizes.

With these and other objects in view, the invention will be hereinafter more fully described with reference to the accompanying 55 drawing forming a part of this specifica-

tion in which similar characters of reference indicate corresponding parts in all the views, and will then be pointed out in the claim at the end of the description.

In the drawing, Figure 1 is an elevation, 60 partly in section and partly in detail, of one form of screw driver embodying my invention.

Fig. 2 is an enlarged sectional view, partly 65 in detail, taken on the line 2-2 of Fig. 5.

Fig. 3 is an elevation of the bit and cap used in the device.

Fig. 4 is a side view of the toothed sleeve used in the tool, and

Fig. 5 is a side view of the handle employed in the tool.

The tool or screw driver has a handle 10 which may be of any material in any appropriate size, and in part of the handle is a socket, as 11, of an appropriate depth. 75 In the socket is a sleeve 12 which is secured to the handle by a pin, as 13, driven through the handle into the sleeve. The portion of the exterior of the handle 10 surrounding the entrance part of its socket may be reduced, as at 14, and the sleeve 12 is of a length so that one of its ends extends beyond the mouth of the socket. On the free edge of this projecting end of the sleeve 12 is an annular row of spaced lugs or teeth 80 15 which are provided by notching, as at 15^a, the sleeve so that the lugs are preferably substantially square or rectangular in shapes.

In the sleeve 12 is rotatably disposed one end portion of a bit or blade, as 16, which 90 is of a length so that its second end portion protrudes some distance beyond the row of lugs 15, and the edge of this second end of the bit may be appropriately sharpened or formed, as at 17, to allow the sharpened end 95 to be arranged in engagement with the seat of the head of a screw or bolt when it is desired to use the tool to rotate the screw inwardly or outwardly of an article in the fashion common to operating tools of this 100 class. The bit 16 is cushioned in the sleeve 12 by a spring, as 18, which is provided in

the bottom of the sleeve for normally serving to force the bit outwardly of the sleeve as well as enabling the bit to yieldingly move 105 inwardly and outwardly of the sleeve. The spring or cushion 18 is also of a size so that the bit normally rests upon the spring within the sleeve some distance from the bottom of the sleeve.

Protruding laterally from the bit 16 in spaced relation to the row of spaced rectangular lugs 15 is a pin 19 of a size as well as being arranged to removably pass within one of the spaces or notches 15^a when the bit is moved a distance accordingly inwardly of the sleeve 12 so that when the bit is in engagement with a screw or bolt and by forcing the handle 10 toward the screw the pin 19 will pass into one of the notches 15^a to cause the bit to be held by the adjacent lugs 15 for being revolved with the rotation of the handle. When a screw or bolt is partly revolved by operating the tool in this manner the bit may be retained in engagement with the screw or bolt, and by relieving the pressure on the handle 10 the tension of the spring 18 will cause the handle to then move to free the pin 19 of the bit from its seat in the notch between two of the lugs 15 of the sleeve 12. By repeating this operation of the handle the bit will be rotatably moved consecutively for facilitating the work of tightening or loosening the screw or bolt as is incident to operating such tools.

The bit 16 is revolvably extended through the central part of a cap, as 20, which is of a size so that it revolvably encircles the reduced part 14 of the handle to inclose the lugs 15 and entrance of the sleeve 12. In order to releasably lock the bit against movement independently of the handle, in the side wall of the cap is a slot, as 21, of somewhat an L-shape so that one of its branches or arms, as 22, is disposed lengthwise of the cap, while the second branch or arm, as 23, of the slot is disposed crosswise or laterally of the cap. Projecting laterally from the reduced part 14 of the handle 10 is a pin 24 which projects into one end of the branch 22 of the slot of the cap. By moving the cap 20 inwardly and then rotating the cap so that the pin 24 will pass into the lateral branch 23 of the slot pin 19 will be held in one of the notches 15^a and the bit and handle will be releasably locked together to be used, in a manner similar to using ordinary types of screw drivers involving a bit or blade rigid with a handle. As the inwardly

projecting flange of the cap 20 is in contact with the lug 19, it will be apparent that the shank 16 will be pushed against the spring 18 into the socket when the cap 20 is positioned so that the lug 24 engages the branch 23 of the bayonet slot. 55

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope thereof. 65 60

Having thus described my invention, I claim as new and desire to secure by Letters Patent:—

A screw driver comprising a blade, a handle associated with said blade so as to be capable of rotary and longitudinal movement relatively thereto, a positive clutch member fixed to said blade, a positive clutch member fixed to said handle, said clutch members being arranged to make a positive clutch connection with each other as they are made to engage each other by the exertion of a longitudinal thrust upon the handle, resilient means for holding said ratchet members out of operative relation, means to retain the handle and blade operative associated, said last named means being operable at will to permit disengagement of the clutch members by the influence of said resilient means or to lock the clutch members in engagement with each other against the action of said resilient means and comprising a cap rotatable on the handle and the blade and longitudinally slideable on the handle and having a bayonet slot, and a laterally projecting pin fixed to the handle and engaging in said slot, said cap engaging the clutch member of the blade.

This specification signed and witnessed
this 29th day of December, A. D. 1920.

JAMES E. McCAFFERTY.
